FIBER GLASS CROSS ARM

William F. Turner, 1/2 Bodendieck Tool Co., Box 499,
Taylorville, Ill. 92568

Filed June 8, 1966, Ser. No. 3,005

Term of patent 14 years

(Cl. D54—1)

FIG. 1 is a top plan view of a fiber glass cross arm, showing my new design;

FIG. 2 is a front elevational view;

FIG. 3 is a bottom plan view;

FIG. 4 is a rear elevational view, and

FIG. 5, is an edge elevational view, taken from the right side of FIG. 4.

I claim:

The ornamental design for a fiber glass cross arm, as shown.
